AUGUST BERNER, OF NUERMBERG, GERMANY, ASSIGNOR TO C. & E. FEIN, ELECKTRO-TECHNISCHE FABRIK, OF STUTTGART, GERMANY.

ROCK DRILL AND LIKE CUTTING MACHINE.

1,417,227.

Specification of Letters Patent. Patented May 23, 1922.

Application filed January 8, 1914. Serial No. 810,949.

(GRANTED UNDER THE PROVISIONS OF THE ACT OF MARCH 3, 1921, 41 STAT. L., 1313.)

To all whom it may concern:

Be it known that I, AUGUST BERNER, a subject of the German Emperor, residing at Nuremberg, in the Empire of Germany, have 5 invented certain new and useful Improvements in and Relating to Rock Drills and like Cutting Machines, of which the following is a specification.

This invention relates to improvements in 10 rock drilling and other cutting machines in which the movement of the hammer piston is operated by the pressure and suction action of a single-acting air pump.

In the ordinary pneumatic tools of this 15 kind the commencement of the suction of the air takes place each time at a given position of the pump piston.

This method of governing the air pressure does not sufficiently meet the actual working 20 conditions, as the movement of the pump and hammer pistons never entirely act in the same or opposite directions. The commencement of the suction of the air should however always be determined by the 25 position of the hammer piston.

According to this invention the commencement 30 of the suction of the air is initiated by the hammer piston itself.

By this invention the commencement of the 35 suction of the air on the completion of the stroke of the hammer piston is effected by an exhaust valve in the hammer cylinder which opens as soon as the stroke of the hammer piston is completed. Consequently 40 the compressed air escapes from the hammer and pump cylinders so that atmospheric pressure is re-established and no additional aspiration is necessary.

Further on the commencement of the suction 45 of the air during the return movement of the hammer piston, the connecting passage between the pump cylinder and the hammer cylinder is connected with the hammer cylinder at a distance from the rear end of the latter which is smaller than the length of the hammer piston. Consequently 50 the suction action on the hammer piston is automatically interrupted as soon as the latter, towards the end of its return movement, has passed the mouth of the connecting passage. The hammer cylinder must of course be made short enough to enable the mouth of the connecting passage to be

passed even in the position of the hammer cylinder in which the full weight of the 55 hammer piston counteracts the suction action.

When the mouth of the connecting passage is covered air is also enclosed between the hammer piston and the rear end of the 60 cylinder. On the further return movement of the hammer piston it compresses the enclosed air until the impetus is destroyed, that is to say the hammer piston is brought to a standstill. At this moment the air between the rear end of the hammer cylinder and the hammer piston is compressed by another stroke of the pump, so that the hammer piston commences to be again driven forward. The commencement of the 70 suction of the air and thereby the change of stroke of the hammer piston takes place accordingly quite automatically by means of the hammer piston independently of the air pump. 75

In order to carry out the stroke which is itself started by the hammer piston, the co-action of the pump is, however, necessary, that is to say the remainder of the air enclosed between the hammer cylinder and the 80 pump cylinder must also be compressed and then again united with the air enclosed behind the hammer plunger. This commencement of the suction of the air by means of the air pump need not take place precisely 85 at the same time as the change of stroke of the hammer plunger, but it can take place somewhat earlier or later without the movement of the hammer piston being thereby influenced. The object sought for, namely the 90 dependence of the commencement of the suction of the air on the position of the hammer piston and the independence of this suction on the position of the pump piston accordingly is attained at least so far as the 95 latter appears necessary in consequence of the relative movements of the hammer and pump pistons caused by the large waste spaces.

The commencement of the suction of the 100 air produced by the pump is operated by a suction valve on the pump cylinder which is uncovered by the pump piston when the hammer piston is near its rear dead point, that is to say, is already enclosed behind 105 the hammer piston. The pump aspirates air

through this valve. Now in order that the pump can immediately commence its compression action at the commencement of its compression stroke, the suction valve according to this invention is so placed that the pump plunger uncovers the valve only towards the end of its suction stroke. The quantity of fresh air aspirated is so large that it replaces not only the unavoidable loss of air, but also the air enclosed behind the hammer plunger.

The combined action of the air compressed by the air pump with the air enclosed behind the hammer plunger takes place at the moment at which the hammer plunger has again been moved forward beyond the mouth of the passage connecting the pump cylinder and the hammer cylinder.

In order that the combined action shall always take place not only at this moment but also when the pressure of the two quantities of air is equal, according to this invention a branch pipe leads from the connecting passage and connects, in direct proximity to the rear end of the cylinder, with the hammer cylinder and is closed by a valve opening into the interior of the hammer cylinder only.

The invention will now be more particularly described in connection with the accompanying drawings, in which one form of construction of a rock drill hammer is illustrated as an example:

Figure 1 shows in longitudinal section on the left a hammer cylinder and on the right hand a pump cylinder.

Fig. 2 is a similar view showing the pistons in different positions.

The movement of the pump piston *i* is produced by a crank drive from an electric motor or the like. The interior of the pump cylinder *k* is connected by ports *l* with a chamber *m* which is closed by a suction valve *h* to the outside air. The upper end of the pump cylinder *k* connects with a pipe socket *o* which is connected with a pipe socket *p* of the hammer cylinder *r* by means of a flexible pipe not shown in the drawings.

The pipe socket *p* is connected with a passage *q* which forks into two branches *g* and *e*. The branch *g* passes axially through the rear end *f* of the cylinder and is closed by a valve *b* which opens to the interior of the hammer cylinder *r* only and which in the example selected is shown as a simple flap valve.

The branch *g* can of course also connect with the side of the cylinder *r*, so long as the mouth lies immediately beneath the end *f*, as it also fulfils its functions under these conditions. The branch *e* connects the two cylinders at a distance from the end *f* of the hammer cylinder which is smaller than the length of the hammer piston *c*.

The hammer cylinder *r* has a pressure

valve *a* which in the example selected is also formed as a flap valve, the aperture *a*¹ of which valve lies at a distance from the tool *s* which corresponds to the length of the hammer plunger *c*. At the bottom portion 70 of the cylinder, ports *v* are provided, so that the chamber beyond the hammer plunger *c* is always in communication with the external air.

In the top end position of the hammer 75 plunger *c* (Figure 1) an air cushion is formed between it and the top end of the cylinder, which cushion operates the change of stroke of the hammer piston. The pump plunger *i* aspirates fresh air through the 80 valve *h*. When the pump makes a compression stroke the air enclosed behind the hammer plunger is united with the air compressed by the pump through the valve *b*. When the hammer plunger *c* has reached its 85 bottom end position (Figure 2) the compressed air escapes through the valve *a* thus immediately reestablishing atmospheric pressure. Of course the ordinary means for controlling heavy and light blows may be 90 arranged in the handle of the tool. It is evident that the invention may be utilized as a hammer tool for all uses and all substances.

I claim as my invention—

1. In a rock-drill or like cutting machine having a hammer cylinder with piston and a single acting air pump for operating it, means for rendering the change of the stroke of the hammer piston independent from the 100 position of the pump piston and make it dependent from the position of the hammer piston, comprising an exhaust valve in the hammer cylinder arranged to open immediately after the forward stroke of the hammer piston whereby the change of stroke is effected after the forward stroke, and a valve in the rear cover of the hammer cylinder producing with its aid during the rearward stroke an air cushion between the hammer 110 piston and the rear cylinder cover, initiating the change of stroke after the rearward stroke.

2. In a rock-drill or like cutting machine having a hammer cylinder with piston and a single acting air pump for operating it, means for rendering the change of the stroke of the hammer piston independent of the air pump, comprising an exhaust valve in the hammer cylinder controlling the change of 120 the piston stroke after the forward movement, a cover on the hammer cylinder forming with the top of its piston an air chamber which houses a compressed air cushion towards the end of the rearward stroke of the piston, said air cushion then controlling the change of the stroke.

3. In a rock-drill or like cutting machine having a hammer cylinder with piston and a single acting air pump for operating it, 130

- means for rendering the change of the stroke of the hammer piston independent of the air pump comprising an exhaust valve in the hammer cylinder controlling the change of its piston stroke after the forward movement, a cover on the hammer cylinder forming with the top of its piston an air chamber towards the end of the rearward piston stroke, and a connection between the pump and hammer cylinders connecting with the hammer cylinder at a distance from the rear cover of the hammer cylinder which is smaller than the length of the hammer piston.
- 15 4. In a rock-drill or like cutting machine, means for controlling the change of the stroke of the hammer piston composed essentially of an exhaust valve in the hammer cylinder establishing atmospheric pressure within the said cylinder at the end of the forward stroke, and an air chamber formed by the cover of the hammer cylinder and the top of its piston housing a compressed air cushion towards the end of the rearward
- stroke of the piston which cushion then controls the change of the stroke.
5. In a rock-drill or like cutting machine, having a hammer cylinder with piston and a single acting air pump for operating it, means for controlling the change of the stroke of the hammer piston comprising a connection having a forked passage in the hammer cylinder, one branch connecting at a distance from the rear end of the said cylinder smaller than the length of the hammer plunger, the other branch connecting directly at the rear end of the hammer cylinder, and a valve located towards the interior of the cylinder adapted to close said second branch and a suction valve in the pump cylinder actuated through the said connection and its forked passage.

In testimony whereof I affix my signature in presence of two witnesses.

AUGUST BERNER.
